UNITED STATES PATENT OFFICE.

CHARLES S. MOSELEY, OF CHICAGO, ILLINOIS, ASSIGNOR OF ONE-HALF TO
CHARLES S. PERRY, OF CHICAGO, ILLINOIS.

TIME-STAMP.

SPECIFICATION forming part of Letters Patent No. 690,910, dated January 7, 1902.

Application filed January 9, 1901. Serial No. 42,610. (No model.)

To all whom it may concern:

Be it known that I, CHARLES S. MOSELEY, a citizen of the United States, residing at Chicago, in the county of Cook and State of Illinois, have invented a certain new and useful Improvement in Time-Stamp, of which the following is a full, clear, concise, and exact description, reference being had to the accompanying drawings, forming a part of this specification.

My invention relates to a time-stamp of the class in which an electromagnet mounted in the base of the time-stamp is adapted to be actuated at intervals by suitable controlling means—as, for instance, a clock—to thereby 15 actuate the indicator mechanism of the time-stamp. This indicator mechanism is usually carried upon the end of a swinging arm mounted upon the base or bed plate; and one 20 of the objects of the present invention is to provide improved means for transmitting motion from the armature of the magnet to the time mechanism.

My invention further contemplates a number of improvements in mechanical detail and arrangement, as will be more particularly set forth hereinafter.

I have illustrated my invention in the accompanying drawings, in which—

30 Figure 1 is a plan or top view of the device of my invention. Fig. 2 is a vertical longitudinal sectional view. Fig. 3 is a bottom view of the base or bed, showing magnet-fastenings and electrical connections. Fig. 4 is a detail view of the indicator-wheels on the line 4-4, Fig. 2. Fig. 5 is a perspective view of the live pawls. Fig. 6 is a side view of block holding the detents. Fig. 7 is a vertical longitudinal section of a modification of my invention.

40 Like letters refer to like parts in the several figures.

In a metallic base or case *a* is located an electromagnet *b*, which may consist of one or 45 more spools, preferably two spools, as shown in the drawings, connected in circuit with the main regulator. Set into the top of the case *a* and flush with the same is a platen *a'*, preferably of rubber, having a canvas facing, 50 upon which when a record is desired the paper or document to be stamped is placed.

The armature *b'* of magnet *b* is mounted on pivots *b*², consisting of screws having recesses in the armature, so that the armature *b'* may vibrate with little friction upon its pivots. 55 The pivots *b*² are kept from working loose by set-screws *b*¹². The screw *b*³, which is threaded into and passes through arm *b*⁴, has a half ball or head *b*⁵ on the end which engages a hemispherical recess or socket *b*⁶ in the lower 60 part *b'*. The opening *b*⁷ in armature *b'*, through which screw *b*³ passes, is conically countersunk, so as to admit of a free swinging movement in recess *b*⁶. The screw *b*³ is 65 conically tapered as it passes through the *b*⁸ countersunk opening *b*⁷. The orifice *b*⁸ opposite the head end of screw *b*³ permits of the adjusting of the arm *b*⁴ by said screw without removing any plates. The arm *b*⁴ is sawed or split at the lower end, thus permitting 70 it to grip the screw *b*³ when screw is tightened, so as not to allow screw *b*³ to work loose. The socket and spherical head permit the armature to freely swing while permitting the partial turning of the rod *b*³ 75 for adjustment without affecting the movement of the armature.

The means for fastening the magnets to the case *a* are as follows: The cores of the magnet *b* are turned down and threaded where 80 they pass through the yoke or cross-bar *b*⁹ and are firmly fastened to case *a* by nuts *b*¹⁰, which are screwed onto the cores of magnet *b*.

Mounted upon base *a* is a hollow rocking arm *c*. This arm is pivoted at its rear end, 85 so that it may rock freely upon pivots *c*', (shown as consisting of screws extending through suitable orifices in lugs *c*²), rising from the case *a*. The forward end of the arm *c* supports an enlarged hollow cap, which fits 90 over an enlarged portion of arm *c*, forming a casing or head *c*³. The hollow cap may be removed for the purpose of obtaining access to the mechanism contained therein by removing screws *c*⁴. The cap *c*³ carries a seat 95 into which is set a dome-shaped piece *c*⁵, of rubber, forming a cushioned handpiece or knob to be engaged by the hand. The rubber piece *c*⁵ is in the form of a flat disk, the edges of which are bent down to fit into the 100 seat and to form the whole into a dome-shaped structure. The swinging arm may be

depressed by the handpiece c^5 , and a spring c^6 retracts the same. The spring c^6 is secured near one end to an arm c^7 , which extends downwardly from the rear end of arm c into the case a and at its other end to a support c^8 , extending from the top case a .

There are eight indicator-wheels in all, six of which are operated to indicate changes in time by the action of the electromagnet. The other two are operated by hand.

The six indicator-wheels which are operated by the action of the electromagnet are mounted side by side loosely upon a shaft d , which is journaled in the side of an enlarged portion of rocking arm c , which fits inside of the hollow head c^8 . These indicator-wheels, which are mounted on the shaft d , work independently of each other, motion being given to them by a number of live pawls d^1 , d^2 , d^3 , d^4 , d^5 , and d^6 , which are mounted upon and form part of cross-bar d^7 . The cross-bar d^7 is provided at its ends with lugs d^8 , through which extends a rod d^9 , journaled at its ends in suitable bearings in side arms d^{10} of a frame d^{11} consisting of a stretcher-bar d^{11} , extending between the side arms d^{10} and secured to the latter at its ends. The side arms d^{10} are loosely hung at their inner ends upon the shaft d inside the month-wheel g and the year-wheel g' , which wheels are mounted on opposite ends of shaft d . The frame is therefore free to move up or down. A coiled spring e , coiled about the rod d^9 and bearing at one end against the bar d^7 and at the other against the stretcher-bar d^{11} , tends to force the pawls d^1 , d^2 , d^3 , d^4 , d^5 , and d^6 toward the indicator-wheels. Each of the indicator-wheels is provided upon its periphery with raised type and upon one of its sides with a ratchet-wheel. The pawls d^1 , &c., in causing the rotation of the indicator-wheels operate upon the teeth of the ratchet-wheels. They are thus caused to operate by a swinging motion which is imparted to the frame carrying the pawls by means of a link e' , pivotally connected at one end to the lever e^2 and at the other to the rod d^9 of the said frame. The indicator mechanism is well known in the art and does not in its individual capacity form a feature of my invention.

Mounted upon the shaft d is the month-wheel g and the year-wheel g' , both of which are operated by hand. Upon the respective indicator-wheels and acting in conjunction therewith are ratchet-wheels, the teeth of which are engaged by the live pawls d^1 , d^2 , &c., and also by the detents e^9 , e^{10} , to prevent backlash. The ratchet-wheel of the unit minute-wheel g^2 has a deep depression into which pawl d^2 , which is of greatest length, drops after having engaged nine of the teeth successively. The pawl d^2 having dropped into said engagement allows the next longest pawl d^3 to engage the ratchet-wheel on tens minute-wheel g^3 , the said ratchet-wheel also having a depression into which pawl d^3 drops every sixty minutes. When both pawls d^2

d^3 are in their respective depressions, the pawl d^4 engages the teeth on the ratchet-wheel of hour-wheel g^4 , said ratchet-wheel also having a depression into which the pawl d^4 drops when the pawls above mentioned have dropped into their respective depressions, so that every twelve hours the two minute-wheels and the hour-wheel move together. When the three pawls referred to are in their respective depressions, the next longest pawl d^5 engages the teeth of the ratchet-wheel of the "a. m." and "p. m." wheel g^5 , which wheel has six depressions, into one of which depressions pawl d^5 drops every twenty-four hours. The teeth on the ratchet "unit" month-wheel g^6 is next engaged by its pawl d^6 , and after having engaged nine teeth the pawl d^6 drops into a depression on said ratchet-wheel. Next in order is the "tens" month-wheel g^7 , the teeth of the ratchet-wheel of said wheel being engaged every ten days.

The lever e^2 is mounted upon a fulcrum e^8 , which is journaled in the walls of rocking arm c . The spring e^4 is bent half around lug e^5 and carried over the fulcrum e^8 and then forward and under lever e^2 and back over fulcrum e^8 and over lug e^5 , and operates to keep the forward end elevated and also to retract the armature b' of magnet b after said magnet is deenergized. The rear end of lever e^2 is slotted to engage the lug e^6 on lever e^7 . The lever e^7 is also mounted upon a fulcrum e^8 , which is journaled in the walls of rocking arm c . The upper end of arm b^4 is pivoted to the lever e^7 at approximately the same center of rotation as the rocking arm c , so that the rocking of arm c will impart no motion to levers e^7 , e^2 , link e' , and pawls d^1 , d^2 , &c. When the electromagnet is energized and the arm b^4 is pulled forward, the lever e^7 is rocked on its joint, which causes the slotted end of lever e^2 to be carried upwardly and the forward end of lever e^2 to be moved downwardly, thereby causing link e' to swing the frame carrying the pawls in a downward direction and moving said pawls far enough to cause one or more of them to engage teeth upon the ratchets of the indicator-wheels. When the electromagnet is deenergized, the spring e^4 operates to move the lever e^2 , the link e' , and the frame and pawls in the opposite direction, thereby causing a rotary progressive movement to be imparted to one or more of the indicator-wheels. Backward movement of the indicator-wheels during the rearward movement of the pawls is prevented by a number of detents e^9 , loosely hung upon a bar f , secured to the walls of the enlarged portion of arm c . These detents engage the ratchet-teeth upon the indicator-wheels and are so constructed as to exactly fit the space between the teeth, so as not to allow of any backlash or play. These detents are held in such engagement by coil-springs f' , bearing upon their upper ends, which are secured in bar f . Said bar f is secured at its ends to the enlarged portion of rocking arm c . The tension of

these coil-springs is regulated by screws f^2 , which screws have counter-screws f^3 , which keep screws f^2 from working loose. The enlarged portion of arm c has a face-plate h inserted in the under side thereof. Both edges of said plate are beveled, one edge fitting an overhanging shoulder or ledge in the head and the other side being held by the head of a screw h' . Said plate has an opening, so as to let the indicator-wheels print on the document. Upon this plate may be mounted such letters or combinations of figures and letters as may be desired, such as the name of an individual or firm. By the removal of the screw h' the plate can be easily removed without disturbing the wheels. Any type mounted on plate h is in the same plane as the printing-type on the indicator-wheels.

Within the bed or base and depending from the upper wall thereof are the standards k k , which support the binding-posts. The standard is provided with an opening or bore, within which fits a shell k' , of insulating material. Within this shell is a rod k^2 , of conducting material, having openings in the opposite ends for the reception of the conductors. Openings k^3 k^3 are provided through the wall of the base for the passage of the leading-in conductors.

Fig. 7 shows a modification of my invention. Instead of using two levers in the rocking arm c to operate the frame which carries the pawls I use but a single lever e^{10} , with a rack e^{11} on the forward end, which engages a pinion e^{12} , which is mounted upon a shaft journaled in the sides of the head. Mounted upon the side of said pinion is a disk h^2 , which carries a pin h^3 , upon which pin a link or connecting-rod is hung, which link is fastened to the pin d^9 . When the armature is attracted by the magnet, the lever e^{10} is rocked on its fulcrum e^{13} , thereby carrying the forward end up and causing the pinion to rotate to the right, thereby causing the link to impart a downward movement of pin d^9 . The spring h^4 retracts the lever e^{10} , thereby causing the same movement as described in the other invention. By employing the rack and pinion the rocking frame which carries the live pawls is caused to start in motion gradually and is gradually brought to rest, due to the fact that the rocking frame is connected with the crank-pin, which during the semirevolution of the pinion imparts motion to the rocking frame by gradually starting the same and then moving the same at a greater speed and gradually bringing the same to rest at the end of the travel, the movement being similar to that of the crank-pin of a steam-engine. The sudden movement of the indicator-wheels and the consequent derangement or misplacement that might follow therefrom is thus effectually avoided.

Having described my invention, what I claim as new, and desire to secure by Letters Patent, is—

1. In a time-stamp, the combination with a

base or bed, of a swinging arm mounted thereon and carrying the indicator mechanism, an electromagnet mounted upon said base or bed, and means for transmitting motion from the armature of said electromagnet to said indicator mechanism, and comprising a rocking lever pivoted at an intermediate point upon said swinging arm and having one end connected with and receiving motion from said armature, and having the other end connected with and transmitting motion to said indicator mechanism, substantially as described.

2. In a time-stamp, the combination with a base or bed, of a swinging arm mounted thereon and carrying the indicator mechanism, an electromagnet mounted upon said base or bed, a rocking lever pivoted at an intermediate point upon said swinging arm and having one end situated approximately concentric with the pivotal axis of said swinging arm and connected with the armature of said electromagnet and having the other end connected with the indicator mechanism, substantially as described.

3. In a time-stamp, the combination with a base or bed, of a swinging arm mounted thereon and carrying the indicator mechanism, an electromagnet mounted upon said base or bed, a rocking lever pivoted to said swinging arm and having one end connected with the armature of said electromagnet, a rack deriving motion from the opposite end of said rocking lever, a pinion adapted to be engaged by said rack and intermediate mechanism for imparting motion from said pinion to said indicator mechanism, substantially as described.

4. In a time-stamp, the combination with a base or bed, of a swinging arm mounted thereon and carrying the indicator mechanism, an electromagnet mounted upon said base or bed, a rocking lever pivoted upon said swinging arm and having one end situated approximately concentric with the pivotal axis of said swinging arm and connected with the armature of said electromagnet, and carrying upon the opposite end a rack, a pinion engaging said rack, a crank-pin moving with said pinion, and a connecting-rod or link extending between said crank-pin and indicator mechanism, substantially as described.

5. The combination with the pivoted armature of an electromagnet, of a part deriving motion therefrom, a rod interposed between said armature and said part, said rod being threaded at one end to engage suitably-formed threads in said part, the opposite end of said rod carrying a head with a spherical surface adapted to engage a correspondingly-formed spherical socket in said armature, substantially as described.

6. The combination with the pivoted armature of an electromagnet, of a part deriving motion therefrom and having a split end, a bore in said split end provided with suitable threads, a rod interposed between said arma-

ture and said part and having a threaded end adapted to engage the threads in said part, a clamping-screw for securing said split end to said rod, the opposite end of said rod carrying a head with a spherical surface adapted to fit a correspondingly-formed socket in said armature, substantially as described.

7. In a time-stamp, the combination with a moving arm, having a head carrying the re-
10 cording apparatus and provided with an upper wall carrying a seat and having a central opening passing through said wall, and a disk of rubber forming a cushion for said moving arm and having its edges compressed
15 and fitting in said seat, said disk being adapted to be passed into position through said central opening from beneath, substantially as described.

8. In a time-stamp, the combination with a reciprocating part carrying the indicator mechanism, and having an opening through which the indicator-wheels are adapted to project, of a face-plate having an opening for the passage of said indicator-wheels, and
25 having one edge adapted to engage an overhanging wall formed on said reciprocating part and a screw extending at an angle to said face-plate, the head thereof being adapted to engage the opposite edge of said face-
30 plate to maintain the same in position, substantially as described.

9. In a time-stamp, the combination with a reciprocating part carrying the indicator

mechanism and provided with an overhanging wall, of a face-plate having one edge 35 formed to interlock with said overhanging wall, and one or more screws extending at an angle to said face-plate, the head or heads thereof adapted to engage the opposite edge of said face-plate to maintain the same in position, substantially as described.

10. In a time-stamp, the combination with a hollow base or bed, of an electromagnet mounted therein, a binding-post mounted upon the inner wall of said base, said base 45 having an opening therethrough, whereby the leading-in wire may pass through said opening to said binding-post, and all of the live parts of the electrical connections be inclosed within said base, substantially as described. 50

11. In a time-stamp, the combination with the indicator-wheels, of a rotatable part carrying a crank, a connecting-rod between said crank and said indicator-wheels and means for moving the part carrying said crank, 55 whereby, due to the interposition of said crank movement, the indicator-wheels are gradually started and stopped, substantially as described.

In witness whereof I have hereunto sub- 60 scribed my name in the presence of two witnesses.

CHARLES S. MOSELEY.
